(57) **CLAIM**

The ornamental design for a playing surface for spinning top toy, as shown and described.

DESCRIPTION

FIG. 1 is a front view of the playing surface for spinning top toy showing our design;

FIG. 2 is a left side view thereof, the right side view being identical to the left side view;

FIG. 3 is a rear view thereof;

FIG. 4 is top view thereof;

FIG. 5 is a bottom view thereof;

FIG. 6 is a perspective view thereof; and

FIG. 7 is a disassembled perspective view thereof;

FIG. 8 is a front view corresponding to FIG. 1 wherein the oblique line hatching has been omitted for clarity of disclosure;

FIG. 9 is a left side view corresponding to FIG. 2 wherein the oblique line hatching has been omitted for clarity of disclosure;

FIG. 10 is a rear view corresponding to FIG. 3 wherein the oblique line hatching has been omitted for clarity of disclosure;

FIG. 11 is a top view corresponding to FIG. 4 wherein the oblique line hatching has been omitted for clarity of disclosure;

FIG. 12 is a bottom view corresponding to FIG. 5 wherein the oblique line hatching has been omitted for clarity of disclosure;

FIG. 13 is a perspective view corresponding to FIG. 6 wherein the oblique line hatching has been omitted for clarity of disclosure;

FIG. 14 is a disassembled perspective view corresponding to FIG. 7 wherein the oblique line hatching has been omitted for clarity of disclosure;

FIG. 15 is a front view corresponding to FIG. 1 but omitting the structure underlying the transparent parts for clarity of disclosure;

FIG. 16 is a left side view corresponding to FIG. 2 but omitting the structure underlying the transparent parts for clarity of disclosure;

FIG. 17 is a rear view corresponding to FIG. 3 but omitting the structure underlying the transparent parts for clarity of disclosure;

FIG. 18 is a top view corresponding to FIG. 4 but omitting the structure underlying the transparent parts for clarity of disclosure;

(Continued)

FIG. 19 is a perspective view corresponding to FIG. 6 but omitting the structure underlying the transparent parts for clarity of disclosure; and,

FIG. 20 is a disassembled perspective view corresponding to FIG. 7 but omitting the structure underlying the transparent parts for clarity of disclosure.

The portions of the playing surface for spinning top toy shown in broken lines form no part of the claimed design.
